CLAIM

I claim the ornamental design for a metronome, as shown and described.

DESCRIPTION

FIG. 1 shows a front view of a metronome;
FIG. 2 shows a back view of the metronome;
FIG. 3 shows a top view of the metronome;
FIG. 4 shows a bottom view of the metronome;
FIG. 5 shows a left view of the metronome;
FIG. 6 shows a right view of the metronome;
FIG. 7 shows the front view of the metronome (with band clasped);
FIG. 8 shows the back view of the metronome (with band clasped);
FIG. 9 shows a perspective view of the top of the metronome (with band clasped);
FIG. 10 shows a perspective view of the bottom of the metronome (with band clasped);
FIG. 11 shows a first perspective view of the top of the metronome (with band unclasped); and,
FIG. 12 shows a second perspective view of the top of the metronome (with band unclasped).

1 Claim, 12 Drawing Sheets
